UNITED STATES PATENT OFFICE.

GILBERT D. GEORGE, OF ST. PAUL, MINNESOTA.

DESIGN FOR AN ENCIRCLING BAND.

SPECIFICATION forming part of Design No. 33,490, dated October 30, 1900.

Application filed October 2, 1899. Serial No. 732,410. Term of patent 7 years.

To all whom it may concern:

Be it known that I, GILBERT D. GEORGE, a citizen of the United States, residing in the city of St. Paul, in the county of Ramsey and State of Minnesota, have invented and produced a new and original Design for an Encircling Band, of which the following is a specification.

In the accompanying drawings, Figure 1 illustrates the invention in perspective, and Fig. 2 is a detail cross-sectional view of the band.

My design comprises a band having a series of cylindrical projections B extending from its face, the projections terminating a distance on each side of a centrally-arranged

rectangular frame D. The upper ends of the projections B are flat, and just below the same the projections are recessed, as at C. At the bottom of the projections B reduced continuations d are formed.

I claim—

The design for an encircling band herein shown and described.

In testimony whereof I have signed my name to this specification in the presence of two subscribing witnesses.

GILBERT D. GEORGE.

Witnesses:

J. S. MACKAY,
M. A. THOMPSON.
